ERNEST E. EPPSTEIN, OF GREAT BEND, KANSAS.

BUNDLE-TYING DEVICE.

1,033,683.

Specification of Letters Patent. Patented July 23, 1912.

Application filed November 22, 1911. Serial No. 661,853.

To all whom it may concern:

Be it known that I, ERNEST E. EPPSTEIN, a citizen of the United States, residing at Great Bend, in the county of Barton and State of Kansas, have invented certain new and useful Improvements in Bundle-Tying Devices, of which the following is a specification, reference being had therein to the accompanying drawing.

10 This invention relates to bundle tying devices, and the principal object of the same is to provide a device which will hold a cord upon a bundle and permit the cord to be easily removed without breaking the cord, 15 thus permitting the cord to be used again.

This invention may be either formed from a strip of resilient wire or may be formed from sheet metal, both forms being shown in the accompanying drawing, wherein:

20 Figure 1 is a perspective view of a bundle having the package tie connected therewith. Fig. 2 is a perspective view of the cord holder shown in Fig. 1.

Referring to Figs. 1 and 2, it will be seen that this invention may be formed of a length of resilient wire which is bent adjacent one end to form the bar 10, the bar 10 being crimped intermediate its length to form the pockets 11. The bar 12 extends 30 at right angles to the bar 10 and is doubled back upon itself to form the fingers 13 and 14. The finger 14 is longer than the finger 13, and is positioned beneath the finger 13 so that the end of the cord may be gripped 35 between the fingers 13 and 14. After forming the finger 14, the wire is bent toward the bar 10 and curved to form the tongue 15 having its inner end 16 bent above the bar 12. A second U-shaped tongue 17 of 40 less length than the tongue 14 is formed next to the tongue 16 and the wire is then carried parallel to the bar 10, and bent intermediate its length to form the hook 18. The end portion 19 of the strip of wire is 45 bent at right angles and carried to the bar 10 where the ends of the bars 10 and 19 are twisted together as shown at 20.

In using this device the cord 21 has one

end tied to the hook 18 and is carried around the package 22 through the pockets 11 and 50 back to the hook 18. The cord is then passed around the hook and carried around the package at right angles to the original direction, between the fingers 13 and 14. After the cord has been passed around the 55 package between the fingers 13 and 14, a sufficient number of times, the string is wound around the hook and has its end portion passed beneath the tongue 15, and between the fingers 13 and 14. The strain of 60 holding the package tied is taken by the hook 18 and the string is kept from slipping by having its end passed beneath the tongue 15, and between the fingers 13 and 14. When it is desired to undo the package, the 65 string is slipped from between the fingers 13 and 14, and from beneath the tongue 15, and then can be easily unwound.

What is claimed is:—

A bundle tying device of the character described formed from a single strip of resilient rod metal bent to a substantially rectangular shape, said strip of rod metal being bent adjacent one end to form substantially rightangularly disposed arms, one of 75 said arms being crimped intermediate its length to form a plurality of pockets, the other of said arms being bent back upon itself to form an overhanging clamping finger, the strip of metal being then bent to 80 form parallel clamping tongues, the outer one being provided with an upwardly curved inner end portion, the remaining portion of the length of metal being bent at right angles to the inner finger and bent 85 intermediate its length to form a bracing hook positioned opposite said pockets, and the end portion of the strip of metal being carried to said first mentioned arm and connected therewith. 90

In testimony whereof I hereunto affix my signature in presence of two witnesses.

ERNEST E. EPPSTEIN.
